ELECTRIC FURNACE UTILIZING CONSUMABLE ELECTRODES AND METHOD OF OPERATING SAME

Robert J. Garmy, Canton, Ohio, assignor to Republic Steel Corporation, Cleveland, Ohio, a corporation of New Jersey

Filed Nov. 22, 1957, Ser. No. 698,256

6 Claims. (Cl. 314—69)

This application is a continuation-in-part of the following copending applications: Serial No. 651,328, filed April 8, 1957, entitled "Cooling Arrangement for Electric Furnace"; Serial No. 671,154, filed July 11, 1957, entitled "Electric Furnace and Method of Operating Same"; Serial No. 670,921, filed July 10, 1957, entitled "Method and Apparatus for Controlling the Atmosphere in an Electric Furnace"; and Serial No. 672,603, filed July 18, 1957, entitled "Electric Furnace Crucible" all of which are continuations-in-part, or divisions of my previous application Serial No. 391,549, filed November 12, 1953, entitled "Method and Apparatus for Forming Ingots," now U.S. Patent No. 2,800,519, issued July 23, 1957.

This invention relates to electric furnaces and particularly to furnaces for producing metallic ingots of high purity. The furnace described herein was designed especially for use with and has successfully been used with metals such as titanium, zirconium and the like, which are difficult to melt because of their high melting points and also because of their high chemical activity at their melting points. This furnace has also been successfully used with other metals, e.g., steel, where an ingot of high purity was desired.

A problem of particular difficulty in connection with furnaces for use in the melting of titanium and the like is the problem of safety with respect to the persons controlling the operation of the furnace and loading and unloading it. The extremely high operating temperatures involved, in the neighborhood of 3140° F. (the melting point of titanium) and the great chemical activity of metals such as titanium and zirconium at their melting points make the probability of an explosion extremely high if oxygen, air or water is allowed to leak into the furnace. Furthermore, if the structural parts of the furnace (which are commonly made of other metals having lower melting points) become overheated, those parts are likely to be destroyed, with resultant contact between the molten titanium and air or water.

Another difficult problem in connection with such furnaces is the difficulty of loading them. The furnace described herein is fed with consumable electrodes formed of titanium and/or other metal to be treated. For example, these electrodes may be compressed from titanium sponge and/or scrap by the method and apparatus described in the copending application of Thomas A. Sindelar, Serial No. 571,810, filed March 15, 1956, entitled "Consumable Electrode Billets and Method and Apparatus for Making the Same." These electrodes are melted in the furnace by means of an arc so that the electrode itself must carry heavy electrical current. In loading such an electrode into the furnace, it is necessary not only to connect it physically to a supporting structure, but also to connect it electrically to a power supply structure. Furthermore, the supporting structure must be adapted to move or feed the electrode to the arc. Since large currents are involved, the electrical connection of such electrodes has in the past been a rather time consuming operation.

2

Although continuously fed furnaces have been suggested, so far as is known, all commercially successful furnaces up to the present, including the furnace disclosed herein, have been batch furnaces, using electrodes of finite length.

Titanium ingots are being produced in increasingly large sizes. In a batch type furnace, which must be shut down after each electrode is consumed for the insertion of a new electrode, the size of ingot which can be produced is limited by the size of electrode which can be fed. Consequently, increasingly larger electrodes are being used to produce the larger ingots, and the problem of supporting such electrodes is becoming increasingly difficult.

It has been the practice in the past to control the feeding of the electrode, in a furnace of the type described, so as to maintain a substantially constant arc voltage. Since the arc voltage is subject to rapid fluctuations, a feeding system of that type requires frequent reversal of the electrode driving motor. Such a system involves a severe stress and indeed even shock to the electrode supporting and driving mechanism with each reversal, and may result in breaking a weak electrode, or shaking it loose from its support.

An object of the present invention is to provide an electric furnace of the type described which is considerably improved from the standpoint of safety. In this connection, an object of the invention is to provide improved safety building structure for housing such a furnace; another object is to provide improved control and operational features for such a furnace; and to provide improved signal and alarm devices for giving to an operator a signal of incipient unsafe conditions in the furnace.

Another object of the invention is to provide improved apparatus for loading a consumable electrode into a furnace of the type described and for making electrical contact to such an electrode.

Another object of the invention is to provide improved mechanism for supporting an electrode in the furnace and for feeding it to the arc.

Another object is to provide an improved method of operating the furnace, including particularly an improved method of control of the rate of feed of the electrode.

The foregoing and other objects of the invention are attained, in the furnace described herein.

The furnace includes a crucible mounted on a truck for horizontal movement along a set of rails. The crucible is supported on the truck by means of a set of jacks so that it may be raised and lowered on the truck. When in its operating position, the crucible is raised on the truck so that its upper end sealingly engages the periphery of an opening in the bottom of a furnace shell.

Mounted on the upper end of the shell is a vertically elongated electrode receiving tube. The electrode supporting mechanism is located above the electrode receiving tube and includes a power tube which extends through a seal in a cover at the top end of the electrode receiving tube and is vertically slidable in that seal.

The mechanism for supporting and feeding the electrode includes a clamp for engaging an end of the electrode. The clamp serves both as a support and as a means for conducting electric current to the electrode. The clamp is removably fastened to a contact plate located at the bottom end of the power tube which extends upwardly through the cover of the electrode receiving tube. The upper end of the power tube is attached by means of terminals and cables to a power supply. The power tube hangs from a crosshead which moves on two vertically extending lead screws. The lead screws hang from a crossbar mounted on two vertical masts. The lead screws are driven concurrently by a motor and

suitable connecting gears and shafts. The entire supporting mechanism, including the motor, the masts, the crossbar, the crosshead, and the power tube and related parts are mounted on a carriage which is movable horizontally and located just below the level of the upper end of the electrode receiving tube. This carriage may be moved between an operating position in which the power tube is aligned vertically with the electrode receiving tube and a loading and unloading position in which the power tube and all the support mechanism are displaced horizontally from above the electrode receiving tube to permit the insertion of a new electrode by means of a crane or the like.

Each electrode clamp is provided with means, for example, horizontal holes, through which rods may be inserted to support it temporarily on the top of the electrode tube. When loading a new electrode, the cover is removed from the electrode receiving tube and is lifted upwardly on the contact plate at the lower end of the power tube. The rods are inserted through the clamp to hang the old clamp and the stub end of the old electrode on the power tube. The contact plate is then disconnected from the clamp and lifted away vertically. The entire supporting mechanism including the carriage then moves horizontally to clear the space above the electrode receiving tube. The old clamp and stub electrode can then be removed by a crane. A new electrode with a clamp attached to its upper end is then inserted in the electrode receiving tube by means of the crane, and is hung on the upper end of the tube by means of inserted rods. The crane and its cables are then unfastened and taken away. The carriage is then restored to its operating position and the contact plate is fastened to the new clamp by means of nuts and bolts. The new electrode is then raised slightly to permit the removal of the temporary supporting rods, and the power tube is then lowered to bring the cover into place. After the cover is fastened, the furnace is ready to proceed with further steps preliminary to a melting operation.

The atmosphere inside the furnace is maintained at a high vacuum during operation. An inert gas is supplied to the furnace to maintain the vacuum at its desired value. The vacuum or subatmospheric pressure inside the furnace is controlled by a pressure regulator at the gas supply.

The feeding of the electrode to the arc is controlled in accordance with a feature of the invention so as to feed the electrode at a substantially constant rate irrespective of minor fluctuations in the arc voltage. A safety control is responsive to the arc voltage and interrupts the operation of the feeding mechanism in the event that the arc voltage goes so high that an interruption of the arc is indicated.

A novel cooling system is provided including a pump supplying a high capacity recirculating system. In the event of failure of the pump, provision is made to cut off the supply of arc current and to transfer the water jackets to a lower capacity standby system which is sufficient to cool the jackets during a cooling down period of furnace operation.

Various safety controls are provided for cutting off the supply of current to the arc in the event that any of a plurality of conditions related to the furnace operation approaches a dangerous value. Such conditions include: the rate of flow of water in water jackets, water supply pressure, furnace pressure, etc.

Various safety signals are provided, some responsive to certain of the operating conditions mentioned above and others responsive to less critical conditions, including for example, the water temperature in the cooling jackets. Controls for the vacuum or subatmospheric pressure inside the furnace and controls for the current in a stabilizing coil are provided by which an operator can terminate a glow discharge condition in the fur-

nace which has been indicated to him, for example, by a rise in the cooling water temperature.

The entire furnace is housed in a building structure so that the crucible and its supporting truck are located in a pit substantially below the ground level. The shell is at or slightly below the ground level, and the electrode receiving tube projects upwardly above the ground level. The length of the tube is determined by the length of the electrodes it is desired to utilize. The practice is to extend the tube upwardly for twelve or fifteen feet.

One side of the crucible chamber is an exterior wall of the building. This wall, called a "blowout" wall, is made structurally relatively weak, while all the other walls enclosing the crucible chamber are made relatively strong. The purpose of this arrangement is that if an explosion occurs in the chamber, the exterior wall is blown outwardly, allowing the force of the explosion to dissipate in that direction, rather than into the building. Outside the blowout wall there is formed a pit in the adjacent earth. The pit is open at the top and has a setback or terrace at the ground level, with a wall a few feet back from the edge of the pit. The pit and the terrace arrangements serve to dissipate the force of the explosion and to direct it upwardly, rather than horizontally against adjacent structures.

The controls, recording and indicating instruments, etc., for the furnace are placed in a control chamber on the ground floor level and on the opposite side of a safety wall from the furnace, preferably being located at a console adjacent a window in that safety wall. A safety window cover is located below the window and is hinged to the wall so that in the event of an explosion at the furnace, it will be blown upwardly and cover the window. The safety cover is always between the window and the furnace. The furnace may be observed through the window by means of a mirror located above the window on the inner side thereof. The control room is provided with a safety exit passage leading through a wall of the building preferably on a side different from that on which the blowout wall is located.

Other objects and advantages of the invention will become apparent from the following description and claims, taken together with the accompanying drawings.

In the drawings:

Sec. 1.—General furnace structure—Figs. 1 to 5

These figures illustrate an electric furnace which is generally indicated by the reference numeral 1. Many details of the furnace structure have been omitted from Fig. 1 for purposes of clarification. The furnace 1 comprises a crucible 2 in which an ingot is formed during operation of the furnace, a generally cylindrical shell or housing 3 above the crucible 2, and an electrode receiving tube 4 which projects upwardly from the shell 3. A truck 9 carries the crucible 2 and is movable between an operating position shown in full lines in Fig. 1 and a loading and unloading position shown in dotted lines.

There are three operating levels for the furnace 1. The lowest level comprises a crucible chamber 5 in which the crucible 2 and the truck 9 are located and from which the crucible 2 and the ingot formed therein are unloaded.

As best seen in Figs. 1 and 4, the truck 9 carries four jacks 27 which may be driven concurrently by means of a motor 28 and suitable gearing, or may be operated individually by means of handwheels 29. The four jacks 27 support a platform 31, best seen in Fig. 5, comprising a steel bottom plate 31a, an electrically insulating plate 31b, and an upper electrically conductive plate 31c. All three of the plates 31a, 31b, 31c have aligned central openings. The bottom of the crucible 2 rests on the platform 31. One edge of the plate 31c is provided with an extension on which is mounted a plu-

5
rality of terminals 32 (Fig. 1) of any conventional construction and of heavy current carrying capacity. The terminals 32 are connected by a like plurality of flexible cables 33 to a like plurality of stationary terminals 34 mounted on a busbar 35. The cables 33 are long enough and have sufficient slack so that the truck 9 may move between its operating position, shown in full lines in Fig. 1, and its loading and unloading position, shown in dotted lines, without disconnecting either the terminals 32 or the terminals 34.

The second operating level of the furnace 1 is the furnace chamber 20. On the floor of this chamber (shown as a steel grating) there is mounted the furnace shell 3. The shell 3 is of a considerably greater diameter than the electrode 36 which extends downwardly through that shell, and consequently provides a substantial annular space around a portion of the electrode as best seen in Fig. 5. At the shell 3 various instrumentalities having to do with the control of the atmosphere inside the furnace are connected, as illustrated diagrammatically in Fig. 23. The shell wall is made double to provide a water jacket 3a (Fig. 5) and its top or head is also double walled to provide a head water jacket 3b.

The electrode tube 4 is mounted on the head of the shell 3 and extends upwardly therefrom a substantial distance, e.g., 12 to 15 feet. The electrode tube 4 is provided to enclose a consumable electrode such as shown at 36 in Fig. 5, which is being fed to the furnace to form an ingot 37 in the bottom of the crucible 2.

The electrode 36 may be of compressed titanium sponge as shown and claimed in detail in the copending application of Thomas A. Sindelar, Serial No. 571,810, filed March 15, 1956, entitled "Consumable Electrode Billets and Method and Apparatus for Making Same."

It has become conventional in the making of titanium ingots to run the titanium through a two-step process. In the first step, an electrode of compressed titanium sponge, as just described, is formed into an ingot having a somewhat larger diameter than the original electrode. This ingot, which has been considerably purified by the elimination of the impurities during its formation, is then passed through a repetition of the ingot forming step. In this second step, the first ingot is used as an electrode and is melted down again in an arc and forms a second ingot of larger diameter. The purpose of the two ingot forming operations is to increase the purity and homogeneity of the final product. The melting down of the material in the arc is very effective to remove those impurities which are gaseous or volatile at the temperatures employed. Since these temperatures are in the neighborhood of the melting point of titanium, namely 3140° F., it may be seen that most impurities are thereby removed. The double operation results in an ingot of high purity and homogeneity. Since titanium is still quite an expensive metal, it is commonly used only where its peculiar heat resistant properties and high strength to weight ratio are of great advantage. Such properties are at their best when the metal or alloy is most nearly free of undesirable contaminants. Consequently, practically all the present demand for titanium and its alloys is for the highly purified forms which may best be manufactured by repeating the melting step.

In any ingot forming operation using consumable electrodes of finite length, there is left a short butt end of the electrode which may not be used without danger to the clamp structure and possible contamination of the ingot. These butt ends are used by welding them to the ends of other butts, or other electrode billets. The welding operation commonly used leaves a groove in the outer surface of the electrode, as shown at 36a in Fig. 5.

The ingots formed in the first melt are considerably shorter and more dense than the compressed billets which are supplied to that first melt. In order to provide an electrode of greater length for the second melt, it is common to weld together two or more of the short electrodes

from the first melt. These electrodes also are characterized by grooves in their outer surfaces at the weld points, as shown at 36a.

The third or upper level of the furnace 1 has a floor 34 (shown as a steel grid) a short distance (two or three feet) below the upper end of the electrode receiving tube 4. This floor supports the electrode feeding and driving mechanism. That mechanism is all mounted on a carriage 38 which moves horizontally between an operating position shown in full lines in Fig. 1 and a loading and unloading position shown in dotted lines in Fig. 1. Mounted on the carriage 38 are two upwardly extending masts 55 connected at their upper ends by a crossbar 56 (Fig. 3). Two lead screws 39 depend from thrust bearings 57 carried by the crossbar 56. The lead screws 39 turn in nuts 110 which are fixed against rotation on a crosshead 41. A power tube 42 depends from a thrust bearing 43 on the crosshead 41. Near its upper end, the power tube 42 carries a bracket 44 to which are attached a plurality of heavy duty terminals 45. The terminals 45 are attached to a like plurality of heavy duty flexible electrical cables 46 (Fig. 1) whose opposite ends are attached to fixed terminals 47 located on a busbar 48.

The power tube 42 extends downwardly through a sealing mechanism 49 (Fig. 3) located on a cover 50 at the top of the electrode receiving tube 4. Below the cover 50, the power tube 42, as best seen in Fig. 5, carries at its lower end a contact plate 51 attached by means of bolts 52 to an electrode clamp generally designated at 53 and described in detail below in connection with Figs. 14 to 16. The electrode clamp 53 engages the upper end of the electrode 36 and not only supports it but serves as a path for conducting electricity to it.

Sec. 2.—Crucible structure and support—Figs. 1, 4 and 5

The crucible structure, the truck and the related mechanisms concerned with the loading and unloading of the crucible on the truck, and the unloading of ingot from the crucible, are not part of the present invention, but are shown and described more completely and claimed in my copending application Serial No. 672,603, filed July 18, 1957, mentioned above.

Furthermore, the specific water jacket structures of the crucible form no part of the present invention, being described more completely and claimed in my copending application Serial No. 651,328, filed April 8, 1957, also mentioned above. However, an understanding of the crucible structure and its related parts are necessary to a complete understanding of certain features of the present invention, particularly those features relating to safety controls and operating controls. For that reason, a brief description of the crucible and the methods of loading and unloading are supplied herein, as follows.

The crucible 2 comprises a generally cylindrical wall section 71 and a base plate 72. The wall section 71 comprises a copper, inner shell 71a and a steel outer shell 71b defining between them a water jacket 71c supplied through a series of inlets, one of which is shown at 74, spaced around the bottom of the jacket. The water jacket 71c has a plurality of outlets 83 peripherally spaced around its upper end. The wall section 71 is provided at its lower end with an outwardly extending flange 71d which is attached by means of a plurality of peripherally spaced bolts 73 to the peripheral edge of the base plate 72.

The base plate 72 comprises a lower plate 72a and an upper plate 72b defining between them a water jacket 72c supplied through a number of spaced inlets 75 and having a central outlet 76.

When a crucible is in place on the platform 31 it rests on the conductive plate 31c, which conducts the electric arc current from the crucible to the terminals 32.

As best seen in Fig. 5, there is provided near the upper end of the crucible wall section 71 an outwardly pro-

jecting flange 77. On the flange 77 rests an insulating ring 78. An insulating cylinder 79 encircles the upper edge of the crucible wall section 71. The insulating ring 78 is adapted to engage the under side of a centering ring 80 attached to a base ring 82 forming a part of the furnace shell 3.

In the electric circuit of the arc, the electrode and its supporting parts are all operated at ground potential, while the crucible and ingot are at a different potential, usually positive. The plate 31b and the rings 78 and 79 insulate the crucible from the other parts of the furnace.

Sec. 3.—Unloading of crucible and ingot—Figs. 1 and 5

After an ingot has been finished in the crucible and the arc current turned off, the water in the cooling jackets is allowed to run for a time long enough to reduce the ingot temperature so that it may be readily handled. The ingot and crucible are then unloaded from the truck 9 by the following procedure.

The inlets 74 for the crucible wall water jacket and the outlets 83 for those jackets, as well as the inlets and outlets for the base plate water jackets, are provided with quick-disconnect coupling 74a, 83a which may be readily removed when preparing to unload the crucible.

A stabilizing coil 84 is wound around the outside of the crucible wall section 71 and is provided with quick-disconnect electrical couplings 85. This coil carries a relatively low current as compared to the current flowing through the electrode and the ingot, and the disconnection of electrical conductors for these relatively small currents is a simple matter and requires little time.

After the ingot has cooled down to a desired temperature, the interior of the furnace is open to the atmosphere by opening a relief valve, thereby breaking the vacuum in the furnace. The jacks 27 are then operated to lower the crucible with the ingot therein, bringing the upper end of the crucible downwardly away from the crucible shell to a position where the upper end of the crucible clears the lower end of the shell and the adjacent floor structures. The motor 54 is then operated to drive the truck 9 to the left as shown in Fig. 1 to the dotted line position underneath an opening 86 in the floor of the furnace chamber 20. This opening may be normally closed during furnace operation by means of a manhole cover or the like.

After the truck has reached its unloading position, the bolts 73 are removed so that the wall section of the crucible is freed from the base section 72. The cooling of the ingot causes it to shrink away from the wall section of the crucible so that the latter section may now be readily lifted off by a crane 87, located at the top of the furnace chamber 20. After the wall section of the crucible is removed, the finished ingot is accessible and may be lifted out by the same crane and removed to the next stage of its manufacturing operation. The base section 72 of the crucible is now lifted off and the truck is then ready for the installation of another crucible which has been prepared to receive an ingot.

The new crucible has had its wall section assembled to its base section by means of the bolts 73 at another location and has a layer of titanium sponge deposited in the bottom of the crucible to assist in starting the arc. This layer may be an inch or so deep over the whole surface, rising in a cone to about two or three inches at the center of the crucible. The truck with the new crucible on it is then run back horizontally to the operating position and the crucible is then lifted by the jacks to bring its upper end into abutment with the lower end of the furnace shell. The quick-disconnect couplings are re-established and the crucible is then ready to proceed with further steps preliminary to the next melting operation of the furnace.

It may be seen that in this unloading and loading operation, there is on separate action required to make or

break the heavy duty electric contacts between the crucible and the power supply cables 33. The cables 33 being flexible, simply sag to the dotted line position shown in Fig. 6 when the truck is moved to the loading and unload station. During this operation, the cables are not electrically charged, the power supply circuit being broken by a remotely located circuit breaker. Simply placing the new crucible on the supporting platform establishes the connection between the crucible and the platform.

Sec. 4.—Electrode supporting mechanism—Figs. 1 to 13

As mentioned above in connection with the general furnace structure, the electrode supporting mechanism is mounted on carriage 38 (Figs. 1, 2 and 13) which moves horizontally between the operating position shown in full lines in Fig. 1 and the loading position shown in dotted lines. The carriage 38 comprises a flat steel plate 88 having a recess 88a (Fig. 13) cut in its front edge. Four slide bearings 89 depend from the plate 88 and slide on a pair of rails 90. Each rail 90 is mounted on three spaced brackets 91 (Fig. 2) attached to an I-beam 98, which forms part of the structure for supporting the floor 34. Underneath each side of the plate 88 and on opposite sides of the respective rails 90, there are attached two steel beams 92 (Fig. 3) of channel-shaped cross-section for stiffening the plate 88.

Near the back central portion of the plate 88 there is mounted a bracket 93 (Fig. 13) which extends downwardly from the plate 88 and supports a reversible motor 94 which drives a traveling nut 95 through suitable gearing. The nut 95 moves along a stationary lead screw 96 attached to a frame member 97 extending between the I-beams 98. By energizing the reversible motor 94, the nut 95 may be driven along the lead screw 96 to move the carriage 38 between its operating and loading positions.

The two masts 55, shown as steel I-beams, are mounted on reinforcing plates 99 at the front part of the opposite sides of the plate 88. Vertical reinforcing plates 100 are provided on either side of both masts, to stiffen the connection between the masts and the plate 88. A pair of guy members 101 are attached at their lower ends to brackets on the plate 88 and at their upper ends to brackets on the masts 55.

The crossbar 56 connecting the tops of the masts is shown (Fig. 2) as comprising a pair of channel shaped beams 56a. The two vertical lead screws 39 are supported on the crossbar 56 by means of combined thrust and guide bearings generally indicated at 57, one of which is shown in detail in Fig. 12. In that figure, the bearing may be seen generally at 102, and includes a tapered outer race 103 fixed on a plate 104 supported on the crossbar 56, a tapered inner race 105 mounted on the upper end of one of the lead screws 39, and a plurality of balls or other antifriction members 106, which run between the races. The upper end of the lead screw 39 is provided with a shoulder 39a to receive the race 105. The race 105 is held against upward movement on the lead screw 39 by a pair of jam nuts 107 and a washer 108.

The crosshead 41 is supported on the two lead screws 39. The crosshead 41 comprises two channel shaped beams 41a held together by means of bolts 109 (Fig. 10). Adjacent each end of the crosshead 41, there is mounted between the two beams 41a a traveling nut structure 110 (see Figs. 10 and 11). Each traveling nut structure 110 comprises two nuts 111 which threadedly engage one of the lead screws 39 and which are separated by a spacer block 112, having an opening at its center to receive an antifriction sleeve 113 through which the lead screw 39 passes. The nuts 111 and the spacer block 112 are held together by means of a plurality of bolts 114. The spacer block 112 has integrally formed with it a pair of oppositely projecting trunnions 115 (see Fig. 10) which extend through openings in the

respective beams 41a, and whose outer ends are threaded to receive nuts 116 which bear against bearing plates 117. Each traveling nut structure 110 is thereby free to pivot for alignment purposes about a horizontal axis 5 extending through the trunnions 115. After alignment is completed, the nuts 116 are tightened.

At each end of the crosshead 41 there is mounted a plate 118 which pivotally supports a pair of flanged rollers 119 adapted to engage the edges of the flanges of the adjacent mast 55. The rollers 119 are horizontally aligned and engage opposite sides of a mast 55 so as to guide the crosshead vertically and to prevent horizontal twisting movements of the crosshead.

At its center, the crosshead 41 supports a bearing block 120 by means of integral trunnions 121 which project from the opposite sides of the block 120 through aligned apertures in the beams 41a. The beams 41a carry bearing plates 122 to take the load on the trunnions. The block 120 has a vertically extending aperture through its center to receive a pin 123 (Fig. 11). An electrically insulating sleeve 123a encircles the pin 123 and insulates it from the block 120. On the lower end of pin 123 there is integrally formed a ball 124 (Fig. 6) which is received in a spherical socket formed in a socket base 125 and a cap 126 threaded onto the base 125. The base 125 is provided on its lower end with an internally threaded socket 125a to receive the threaded upper end of power tube 42. Concentric with the socket 125a, and opening into the upper end thereof, there is provided a central passage 125b which communicates with a laterally extending passage 125c adapted to receive an external water supply coupling member 127. Another passage 125d is provided to receive another coupling member 128 and to provide communication with the socket 125a. A water pipe 129 is concentric with the power tube 126 and has its upper end received in the opening 125b. The lower end of the water pipe 129 is provided with a plurality of wings 130 which support its lower end above a plug 131 which closes the lower end of the power tube 126. The couplings 127, 128, the various passages in the socket base 125 and the water tube 129 cooperate to provide a path for circulating coolant, e.g., water, from coupling 127 through central pipe 129, out through its lower end, up through the power tube 129 and out the coupling 128. The coolant is necessary because the power tube 126 carries heavy electrical currents and tends to become overheated due to the power loss in the resistance of the tube 126.

Just below the socket base 125 there is mounted on the power tube 126 the terminal block generally indicated by the reference numeral 44. The terminal block 44, as best seen in Figs. 6 and 9, comprises a pair of plates 131, a pair of spacer blocks 132, a plurality of bolts 133 holding the plates 131 and the blocks 132 together and clamping the assembly on the tube 42. A plurality of cable tip connectors 134 are attached to the ends of the plates 131 by means of bolts 135. The cable tip connectors 134 are attached to the ends of cables 46 (see Fig. 1). The cables 46 are flexible and have sufficient slack to allow movement of the electrode supporting mechanism between its operating position and its loading and unloading position. This slack is also sufficient to allow the vertical movement of the terminal block 44 between the upper and lower positions shown in Fig. 1.

At an intermediate locality along its vertical length, the power tube passes through a seal and joint structure 49 and through an aperture 50a formed in the center of the cover 50 of the electrode tube 4. The seal and joint structure 49 comprises a socket formed in upper and lower socket blocks 136, 137, and a ball 138 having a central vertically extending aperture to receive the power tube 42 and a spherical outer surface which rides in blocks 136, 137. O-ring seals 139 are provided between the ball 138 and the power tube 42.

The lower end of the power tube 42 is threaded into a recess in the contact plate 51. The power tube 42 and the contact plate 51 are fixed together by means of a lock nut 141. Nuts 52 cooperating with studs 52a (see Fig. 17) provide for attachment to the contact plate 51 of the electrode clamp 53 which is described in detail below in connection with Figs. 14 to 16.

It should be noted that the ball 138 and its cooperating socket, together with the ball 124 and its cooperating socket allow considerable freedom of lateral and angular movement of the power tube relative to the crosshead, and vice versa. These joint structures thereby prevent binding of the various parts during operation of the furnace.

The electrode supporting mechanism described above is driven vertically through the lead screws 39, which are in turn driven by power actuating mechanism best illustrated in Figs. 13 and 2. This mechanism includes a motor 143 connected through a coupling 144 to a speed changing transmission 145 and thence through a coupling 146 to a right angle speed reducer 147. The output shaft of the speed reducer 147 is connected through a coupling 148 and a slip friction clutch 149 to a miter gear unit 150 having two output shafts 151 and 152 extending at right angles to each other and connected through suitable couplings to right angle miter gear units 153 and 154 respectively connected to the bottoms of the lead screws 39. The lower ends of the lead screws 39 extend through guide bearings 155 (Fig. 3) mounted on the masts 55, and are connected to the gear units 153 and 154 through couplings 155a of a conventional type, constructed so that they do not transfer any thrust to or from the lead screws 39.

The load of the electrode is applied to the lead screws 39 through the cross-head 41, and the lead screws are supported only at their upper ends by bearings 57. Consequently, the lead screws are stressed only in tension, in which condition their strength is greatest.

A tachometer generator 344 is driven from the output shaft of motor 143. A telemetric generator 140 is driven from one of the output shafts of gear unit 150, and is connected to an integrating receiver on the control panel to provide the operator with an indication of the position of the electrode.

Sec. 5.—Electrode changing operation

At the end of a run, the electrode clamp 53 in the furnace will have connected to its lower end a short electrode butt. The operation of removing this butt and replacing it with a fresh electrode for a new run of the furnace will now be described.

After the arc current is shut off at the end of the run, the motor 143 is reversed to drive the lead screws 39 in the direction to move the crosshead 41 upwardly, thereby carrying with it the power tube 126, and the clamp 53 with the electrode butt attached thereto. The vacuum inside the furnace is relieved so that it does not tend to hold the cover in place on the end of the electrode tube 4. When the contact plate 140 engages the under side of the cover 50, the cover is lifted from the end of the electrode tube 4. The upward movement of the electrode butt and its related parts is continued until horizontal holes 53a formed in the electrode clamp 53 are at a level somewhat above the top of the electrode tube 4. Rods 156 (Fig. 17) are then inserted through the holes 53a. The electrode clamp is rotated by means of rods 156 until they are in line with saddles 157 mounted on the upper end of the electrode tube 4. The motor is then driven to move the electrode clamp downwardly until the rods 156 rest in the saddles 157. The weight of the electrode butt and the clamp 53 is now taken by the rods 156. The nuts 52 are then removed. After removal of the nuts 52, the motor 143 is again driven to move the power tube 42 and its related parts upwardly to the uppermost position shown in Fig. 1.

After these parts reach that position, the motor 143 is stopped and the motor 94 is actuated to move the carriage 38 back to the dotted line position shown in Fig. 1. The clamp 53 is now free overhead for access by a crane shown diagrammatically at 158. A ring pin 158a (Fig. 17) is inserted in a threaded hole 53b (Fig. 8) formed in the upper surface of the electrode clamp to receive the hook of the crane 158. The electrode butt and the clamp are then lifted by the crane 158 and taken to another location where the butt may be disassembled from the clamp.

A new electrode with a clamp 53 assembled thereon is then moved into place by the crane 158, and lowered into the electrode tube 4 until the holes 53a in the clamp are slightly above the saddles 157. The rods 156 are then inserted in the holes and are aligned with the saddles whereupon the crane lowers the clamp until the weight of the electrode and clamp is taken by the rods 156. The crane is then unhooked and the ring pin removed from the clamp 53.

The motor 94 is now operated to move the carriage 38 into its operating position. When it reaches that position, the motor 143 is run to lower the power tube 42 and the contact plate 51 until the latter comes into engagement with the electrode clamp 53. The nuts 52 are inserted to fasten the contact plate to the electrode clamp. The motor 143 is then run to lift the electrode slightly and take the weight off the rods 156. The rods are thereupon removed and the motor 143 is then run to drive the electrode downwardly until the cover 50 again rests on the top of the electrode tube 4. The cover may be clamped in place by means of C-clamps, or any other suitable means. After the furnace is evacuated, as it is during operation, the difference between the external pressure and the internal pressure tends to hold the cover 50 in place so that the C-clamps may then be removed.

Sec. 6.—Electrode clamps—Figs. 14 to 18

Two species of electrode clamps are shown in Figs. 14 to 16 and Figs. 17 and 18 respectively. The specific clamping structures shown herein are described more completely and claimed in the copending application of Arthur F. Jones and Donald A. Rice, Serial No. 697,702, filed November 20, 1957.

The clamp of Figs. 14 to 17 comprises a clamp body 160 which is generally T-shaped in vertical cross-section, having a central stem portion and an upper flange portion 160a. Near its upper end, the stem portion is provided with four grooves 160b for receiving four pivot pins 161. The pivot pins 161 are held in place in the grooves 160b by means of screws 162. Four clamp arms 163 are attached to the outside of the clamp body 160 by means of bolts 164. The lower ends of these clamp arms tightly engage the sides of the end of an electrode, as best seen in Fig. 14. The surfaces of the clamp arms facing the electrode may be variously contoured to accommodate various electrode shapes. It should be understood, however, that it is not necessary to have an exact or even a close matching of the clamp arm contours and the electrode contours. The clamp arms 163 are tightened against the end of the electrode by means of the bolts 164. The tightening of these bolts accommodates minor variations in the electrode contour and also tightens the upper ends of the clamp arms against the pivot pins 161. The upper ends of the clamp arms are provided with grooves 163a which are cylindrical in contour, conforming to the pins 162 so that the clamp arms can pivot freely on the pins 162 during the tightening of the clamp arms against the electrode end.

The clamp is assembled on the electrode with the lower end of the clamp body abutting against the end of the electrode, which may have a rough irregular contour. The principal path of flow of electrical current to the electrode is through the body 160, the pins 162, downwardly through the clamp arms 163 and thence through

the sides of the electrode. Relatively little current is carried through the end of the electrode and the abutting surface of the clamp body 160, since those surfaces are not forced together tightly by the clamp mechanism.

The electrical disconnection, and connection of an electrode to the arc circuit may be accomplished during the loading and unloading of the furnace by the relatively simple mechanism described above in Sec. 5, involving the removal and replacement of nuts 52 (Fig. 5) from studs 52a (Fig. 17). The detachment of the electrode furnace from its supporting structure also serves to disconnect it from the heavy current arc circuit. The operation of attaching the clamp 53 to an electrode may be performed at a location remote from the furnace, while the furnace is operating, to prepare the electrode for use in the furnace. The shutdown time of the furnace between runs is thereby decreased, since it is not necessary to keep the furnace shut down while a high capacity electrical connection is made to the electrode structure itself.

Figs. 17 and 18 show a modified form of electrode clamp generally indicated by the reference numeral 165. The principal difference between this clamp and the one in Figs. 14 to 16 is that the electrode body 166 is triangular in horizontal cross-section instead of being rectangular as in the case of the body 160. The clamp 165 uses three clamp arms 167 instead of the four clamp arms of Figs. 14 to 16. The three clamp arm arrangement is sometimes better for handling electrodes of certain contours.

Sec. 7.—Electrode guide structures—Figs. 19 to 22

These figures illustrate two species of electrode guide structure which is fixed to the inside of the electrode receiving tube 4, as shown in Fig. 21. Figs. 19 to 21 illustrate one species which comprises a plurality of spacer rings 168 which are held in vertically spaced relationship by a plurality of stretchers 169. The stretchers 169 are shown as formed of angle irons and have their angular corners extending inwardly from the spacer rings 168, as best seen in Fig. 25. The corners of the stretchers 169 fit between the clamp arms 163 (see Fig. 21), so that when an electrode is lowered into the tube 4, the stretchers 169 prevent rotation of the electrode in the furnace.

Fig. 22 illustrates an alternative and more simply constructed form of electrode guide which may be used in place of that shown in Figs. 19 to 21. This electrode guide consists of a steel cylindrical tube 350 having a plurality of flanges 351 welded to its periphery at spaced points along its length, with two of the flanges near the ends of the tube 350. The end flanges are braced by means of triangular webs 352. A plurality of holes 350a are located at spaced intervals along the tube 350, to facilitate handling thereof by means of a crane.

The electrode receiving tube and guide are usually operated at the same potential as the electrode itself, commonly ground potential. Consequently, it is permissible for these parts to come in contact during operation. On the other hand, the crucible is at a different potential (usually positive) from the electrode, and it is desirable to maintain the lateral spacing between the electrode and the crucible so as to ensure that the arc forms only between the end of the electrode and the forming ingot. The guide maintains that lateral spacing by holding the ingot against swinging movements. In effect, it serves as an adapter to accommodate differences between the inside diameter of the electrode receiving tube and the outside diameter of the electrode. If an electrode of different outside diameter is to be used, then a guide of different diameter is substituted.

The guide structure of Figs. 19 to 21 engages the sides of both the clamp and the electrode, while the guide of Fig. 22 engages the clamp only. If the electrode dimensions are oversize, the guide of Figs. 19 to 21 may oc-

casionally bind an electrode. However, the guide of Fig. 22 operates satisfactorily even with substantially oversize electrodes.

Sec. 8.—Atmosphere control system—Fig. 23

This figure illustrates diagrammatically the system for controlling the pressure of the atmosphere inside the furnace. A vacuum pump 170 is connected through a dust filter 171 to the furnace shell 3, and discharges to the atmosphere, preferably outside the building. An inert gas supply system, including an argon tank 173 and a helium tank 178, supplies to the furnace, a mixture of those gases (or either gas alone, as preferred in a particular situation). The gas flows from the argon tank 173 through a pressure regulating valve 174, a flow meter 175, a needle valve 176 and a conduit 177 to the furnace shell 3. Similarly, helium flows from the tank 178 through a pressure regulating valve 179, a flow meter 180 and a needle valve 181 and the conduit 177 to the shell 3.

The furnace shell 3 is provided with two large outwardly extending conduits 182 and 183. At the outer end of each of the latter conduits there is provided a large rupture disc 184, only the one on the conduit 182 being shown. These discs are set to rupture at a predetermined pressure (commonly 18 pounds per square inch gage for a furnace adapted to operate with an internal atmospheric pressure of 50 to 100 microns). The purpose of the rupture disc is to relieve internal pressures which may be developed, due to faulty operation or structural failure within the furnace. The conduit 177 supplies gas to the conduit 182. The conduit 185 leading to the vacuum pump 170 is connected to the conduit 183. The connection of the conduits in this manner maintains a flow through the conduits leading to the rupture discs and tends to minimize the deposit of dust or foreign materials in those conduits. Furthermore, the conduits 182 and 183 run cooler than the shell 3. A gage 186, which may be located remotely from a furnace, for example in the control room (see Fig. 29), is connected to the conduit 182 so that the furnace operator has constantly available a measure of the pressure in the furnace. An excess pressure control device 187 is connected to the conduit 182. Another excess pressure control device 188 is connected to the conduit 183. As explained below in connection with the safety control system, the control devices 187 and 188 operate to cut off the supply of electrode current in the event of excessive pressures being established inside the furnace shell 3.

The pressure regulator valves 174 and 179 associated respectively with the argon and helium tanks are all connected to a common control device 189, located preferably in the control room. The regulators 174 and 179 should also be independently operable from the control room. The device 189 may operate through a pneumatic line or any other suitable remote control system.

Sec. 9.—Coolant supply system for cooling—Fig. 24

This figure illustrates diagrammatically the system for supplying water to the various cooling jackets associated with the furnace. The system illustrated is a recirculating system and depends upon the city main or other primary supply only for makeup water or for emergency use in case the recirculating system fails. If a coolant other than water is used, a standby supply is employed in place of the primary supply mentioned above. The system includes a tank 211. Water flows from the tank 211 through a filter 212 and a valve 213 to the recirculating pump 214 provided with a regulating valve 215 which maintains a nominally constant discharge pressure. Water flows from the pump 214 through a manifold 216 and a check valve 217 to a conduit or manifold 218 leading to the crucible base water jacket 220 and a conduit 75 or manifold 219 leading to the crucible wall water jacket

221. Each of these water jackets actually has multiple inlets which are supplied from a manifold structure. In the diagrammatic Figure 24, the manifolds are shown as single conduits, for the sake of simplicity. A branch conduit 222 leads to the furnace head water jacket 3b and the furnace shell water jacket 3a. The branch conduit 222 also supplies the electrode support or power tube jacket 225.

Water discharged from the crucible base water jacket 220 passes through a conduit 226, a rate of flow responsive telemetric transmitter 227 and a discharge conduit 228 into a sink 229. Water discharged from the crucible wall water jacket passes through a rate of flow responsive telemetric transmitter 230 and a conduit 231 to the sink 229. The furnace head water jacket 3b, furnace shell water jacket 3a and the electrode support jacket 225 discharge through conduits 232, 233 and 234 respectively to the sink 229. The sink 229 is open at the top, and is located within the furnace chamber 20 at a location (see Fig. 31) where it is visible to the operator looking through the window 22. It therefore provides the operator with a direct visible check on the fact that water is flowing through all the cooling jackets. The operator also receives from his observation of that sink a rough indication of the presence of any excessive temperature in any cooling jacket. This indication is a change from the normal condition of the vapor rising from the sink.

The sink 229 discharges back into the tank 211 through a conduit 235.

Makeup water is received from the city main or other suitable source through a conduit 236, a valve 237 and a valve 238 in a conduit leading directly into the tank. Water may also flow from the valve 237 through a bypass conduit 239 controlled by a manual valve 240 and an automatic valve 241. A check valve 242 is located downstream from the valve 241 in order to prevent reverse flow through the bypass line.

Five low pressure control devices identified by the reference numerals 243a, 243b, 243c, 243d and 243e are connected at individual points in the water supply system, as described in detail below. The function of all these low pressure control devices is generally the same, i.e., to cut off the supply of electric current to the arc in the event that the pressure at its particular control locality falls below a desired minimum. The electric circuit by which these low pressure control devices operate is described below in connection with the safety control system of Fig. 27. The use of a multiplicity of such devices increases the safety of the system, since it increases the number of localities where pressure drops may be detected and also increases the rapidity with which a pressure drop may be detected. Such pressure drops are indicative of either leaks, water supply failures, or pump failures.

Control device 243a responds to the pressure at the outlet of the pump 214. Control device 243b responds to the pressure at the inlet of the manifolds leading to the crucible water jackets. Control device 243c responds to the city main pressure, measured between the manifold valve 240 and bypass valve 241. Control device 243d responds to the pressure at the inlet to the furnace head and shell water jackets. Control device 243e responds to the pressure at the inlet to the electrode support or power tube cooling jacket.

The valve 241 is biased to open position by a spring 244, and is normally held closed against that spring by a diaphragm 245 subject on its right-hand side, as it appears in the drawing, to the pressure at the discharge side of the main pump 214 and subject on its left-hand side to atmospheric pressure. When the discharge pressure of pump 214 falls below a predetermined value established by the strength of the spring 244, then the valve 241 moves to open position, allowing the water to flow from the city main or other standby supply, direct

into the crucible water jackets. The check valve 217 then prevents backflow from the city main through the pump 214 or through the other jackets.

It should be borne in mind that if the discharge pressure of pump 214 fails, the low pressure control 243a immediately operates to shut down the arc current, thereby terminating the heating in the furnace. The valve 241 operates at the same time to switch the water jackets to the city main, so that the cooling of those jackets may continue for the time necessary to cool the crucible, to avoid an explosion which might occur if the water in the jackets were allowed to stop flowing. Such a termination of flow might result in development of steam pressure in the jackets.

Thermostats 202, 207 and 208, whose electrical function is described below in connection with Fig. 26, are located, as illustrated diagrammatically, in Fig. 24, at the outlets to the respective water jackets.

Sec. 10.—*Current supply control for stabilizer coil—Fig. 25*

This figure illustrates a wiring diagram for supplying current to the stabilizer coil shown at 84 in Fig. 5 and shown diagrammatically in Fig. 25. This coil provides a vertically directed magnetic field inside the crucible which is effective to confine the arc to the central portion of the crucible and to prevent it from becoming established between the side of the electrode 36 and the copper shell 71a of the crucible. This field also cooperates with the field due to the current flowing in the molten metal to stir that metal.

The coil 84 receives power from a three-phase alternating current supply line 190, 191, 192 through the contacts of a relay 193 and a rectifier generally indicated at 194. The rectifier 194 is provided with an output current control including a rheostat 195 by which the output current may be varied over a predetermined range. Two of the three lines of the A.C. supply are provided with overload relays 196 and 197 having contacts 196a and 197a respectively.

A circuit for a recorder 360 is provided with energy from one phase of the three-phase supply through a transformer 198. The transformer 198 also supplies an energizing circuit for the winding of relay 193. This circuit may be traced from one terminal of the secondary of transformer 198 through a manually operated switch 199, relay winding 193 and overload relay contacts 196a and 197a, back to the opposite terminal of the transformer secondary.

In addition to the power line contacts, the winding 193 operates a back contact 193a controlling a red signal light 200, and a front contact 193b controlling a green signal light 201.

A temperature pick-up unit 361, of any suitable type, e.g., a thermocouple, responsive to the temperature of the water leaving the crucible wall cooling jacket, controls the position of the stylus on the recorder 360.

In the absence of other external causes, such as low coolant pressure or reduced flow, a sudden increase in temperature at the outlet of the crucible wall water jacket 60 may be an indication of the establishment of a glow discharge between the electrode and the inner copper shell of the crucible. Such a glow discharge produces heat at the copper shell, thereby reducing the amount of energy available at the arc and also increasing the temperature of the water in the cooling jacket. It has been found that the establishment of such a glow discharge is always accompanied by a sudden increase in the temperature of the water leaving the crucible wall cooling jacket. The operator watches the record chart made by the recorder 360, and if he observes a sudden sharp increase in the temperature of the crucible wall cooling jacket, then he knows that a glow discharge has started.

The operator can remedy the situation by operating the rectifier control rheostat 195 to increase the current

flow through the coil 84 and thereby to increase the magnetic field which stabilizes the arc. Alternatively, the operator may inhibit such a glow discharge by operating the regulator 179 of Fig. 23 to increase the pressure of the atmosphere inside the furnace and the proportion of helium in that atmosphere. Either or both of these remedies may be applied increasingly until a drop in temperature of the crucible wall coolant is observed, indicating that the glow discharge has been stopped.

Sec. 11.—Signal System—Fig. 26

A thermostatic switch 202, responsive to the temperature of the water leaving the crucible wall cooling jacket, operates a contact 202a controlling a red signal 203 and a green signal 204. A thermostat 207 responsive to the temperature of the water leaving the crucible base cooling jacket operates a contact 207a which controls a red signal 205 and a green signal 206. A thermostat 208 responsive to the temperature of the water leaving the power tube cooling system operates a contact 208a which controls a red signal 209 and a green signal 210. All these signals are supplied with electrical energy from lines 362 and 363. When all the temperatures are below predetermined limiting values, the green signals are energized. In any of the temperatures rise above its limiting value, its red signal is energized. The operator may then seek the cause of the high temperature and try to correct it before it causes a shutdown of the furnace.

Sec. 12.—Safety control system—Fig. 27

This figure illustrates diagrammatically the wiring diagram for the power supply system for the arc circuit. The system includes a circuit breaker 247, manual controls for operating the circuit breaker and automatic controls for tripping the circuit breaker upon the occurrence of any of several potentially dangerous conditions in the furnace.

The power supply for the electrode circuit of the furnace comes from a three-phase A.C. power line 248, 249, 250. The current flows from these lines through the contacts of the circuit breaker 247 to a bank of rectifiers schematically indicated at 251 which supply the electrode circuit of the furnace, which is schematically indicated at 252. The circuit breaker 247 is provided with a closing coil 253 and a tripping coil 254. The circuit breaker is of the type which latches in either of its closed or tripped positions by mechanical means. In order to transfer it from one of its positions to the other, it is necessary to energize the proper coil for a short interval.

The closing coil is energized from a single circuit which may be traced from the line 248 through coil 253, a contact C of a manual switch 255 and thence through a wire 256 to supply line 249. The tripping coil 254 also has an energizing circuit controlled by switch 255, which may be traced from line 248 through coil 254, contact T of switch 255 and line 256 to power supply line 249.

The circuit breaker 247 operates a contact 247a which controls the energization of red and green signal lights 257 and 258. Red signal light 257 is energized through an obvious circuit when the main contacts of the breaker are closed, and green signal light 258 is energized when the main breaker contacts are open.

An emergency circuit for energizing the tripping coil 254 extends through that coil and a push button switch 365, located at the principal control station. Other emergency controls for manual operation at other localities may be provided if desirable.

A group of automatic controls is provided for energizing the tripping coil in response to the various low water pressure controls 243b to 243e inclusive. Only one such control is shown in the wiring diagram, for purposes of simplification. As there shown, the water pressure control operates an expansible bellows 261 connected to a switch finger 262. The switch finger 262 is normally open

but if the pressure in the bellows 261 drops below a predetermined value, the switch 262 closes, completing an energizing circuit between conductor 256 and a conductor 263 which is connected in series with the tripping coil.

Another safety control operates in response to the water pump discharge pressure and is provided with a latching relay and with signals. The pump discharge pressure responsive control device 243a is connected to an expansible bellows 265 which operates a switch finger 266 movable between two stationary contacts. In the normal position shown, the switch 266 completes an energizing circuit for a green signal light 267. This circuit may be traced from power supply line 248 through a conductor 268, switch 266, signal light 267 and a conductor 269 back to power supply line 249. If the pump discharge pressure falls below a predetermined value, the switch 266 moves to its opposite circuit closing position, where it completes an obvious circuit for a red signal light 270 and for the latching winding 271 of a latching relay generally indicated at 272. The latching relay has a contact 273 connected between the conductors 256, 263, so that when the relay is latched it completes a circuit for the tripping coil 264 of circuit breaker 247. The latching relay has a holding contact 274. When the relay is latched, contact 274 completes a circuit for the winding 271 which may be traced from power supply line 248 through wires 268 and 275, normally closed contacts of a manually operable push-button switch 276, the contact 274 and latching winding 271 to wire 269 and thence to power supply line 249.

Energization of the latching winding 271 results in closing of contact 273, thereby energizing the tripping coil 254 of the circuit breaker 247, cutting off the supply of current to the furnace arc and shutting the furnace down. The latching relay 272 may be reset manually by operating the push-button switch 276, which has a set of normally open contacts controlling an obvious energizing circuit for the unlatching winding 277 of the relay 272.

The three control devices 227, 230 and 246 of Fig. 28, which respond to the rate of water flow through the various cooling jackets, cooperate to control a green signal light 278, a red signal light 279, and a latching relay 280. The rate of flow responsive control devices may be simple flow responsive switches including an orifice or Venturi in the line whose flow is to be measured and a diaphragm subject to the pressure drop across the orifice or between the entrance and the throat of the Venturi. The diaphragm or other control device is connected to a switch finger. The several switch fingers are respectively identified as 227a, 230a and 246a. These switch fingers are connected in parallel. Each of the three switch fingers is movable between a normal position in which it connects conductor 268 to a conductor 281 in series with the green signal lamp 278 and an emergency position in which it connects conductor 268 to a conductor 282 which is connected in parallel to the red signal lamp 279 and the latching winding 283 of latching relay 280. The latching relay 280 also has an unlatching winding 284 controlled by a manually operable reset switch 285. The operation of the latching relay and the reset switch 285 is entirely analogous to the operation of the latching relay 272 and reset switch 276 described above. A detailed description of latching relay 280 and reset switch 285 is therefore considered to be unnecessary.

Fig. 23 are shown in Fig. 27 to control a red signal lamp 286, a green signal lamp 287 and a latching relay 288. The latching relay 288 is provided with a manual reset switch 289. The pressure controls 187, 188 operate switches 187a and 188a between normal positions shown in the drawing in which they connect conductor 268 to a conductor 290 connected in series with the green signal lamp 287, and an emergency position in which they connect conductor 268 to a conductor 291 which supplies the red signal lamp 286 and the latching relay 288 in

parallel. The switches 187a and 188a are moved to their emergency positions whenever the pressure inside the furnace exceeds a predetermined value. The operation of the latching relay 288 and the reset switch 289 is analogous to that of relay 272 and reset switch 276, and will not be repeated in detail.

Sec. 13.—Electrode drive motor control system—Fig. 28

The wiring diagram for Fig. 28 is highly simplified, so as to illustrate and emphasize those features which are important to the present invention. Many common motor control systems are suitable for modification to include such features, providing they have provision for variable speed and for forward and reverse operation of the motor.

The system illustrated includes a direct current power supply 300, a motor speed control 301 including a rheostat 302 adjustable by means of a manual knob 303, a "raise" relay 304, and a "lower" relay 305, both controlled by a manual selector switch 306. The instrumentalities just described cooperate to control the motor 143 (see also Fig. 13) which operates the electrode drive mechanism shown diagrammatically in Fig. 28 at 307. Current flows from the power supply 300 through line wires 308 and 309 to the motor speed control 301. This may, for example, be a Ward Leonard variable speed motor control system. Current flows from the motor speed control 301 through wires 310 and 311 and the contacts of the relays 304 and 305 to the motor 143. When the relay 304 is energized, its contacts are closed and the motor energizing circuit may then be traced from wire 310 through contact b of relay 304, the motor 143 and contact a of relay 304 back to wire 311. When relay 305 is energized, the motor energizing circuit may be traced from wire 310 through contact b of relay 305, motor 143, and contact a of relay 305 back to wire 311. It may be seen that the polarity of the motor with respect to the wires 310 and 311 is reversed when relay 305 is energized as compared to its polarity when relay 304 is energized.

The energizing circuit for relay 304 may be traced from a supply line 312 through the "raise" contact of switch 306 and the winding of relay 304 to a supply line 313.

The energizing circuit for relay 305 may be traced from supply line 312 through the "lower" contact of switch 306, the winding 305, and thence through contact 314a of relay 314 in parallel with a push-button reset switch 315 to the supply line 313.

Relay 314 is of any suitable voltage sensitive type and its winding is connected across the arc at the electrode, schematically indicated at 252. This relay is set to have its contact 314a in its back or circuit-closing position whenever the arc voltage is in a range of values indicating that an arc exists at the electrode. When the arc voltage increases to a value indicating that the arc has been interrupted, the relay 314 picks up its contact 314a opening the circuit connected therethrough.

A recorder 316 of any suitable type, is also connected across the arc voltage and makes a continuous record thereof. The motor 143 drives a tachometer generator 317, which is connected in a simple series circuit with a tachometer 318. The tachometer 318, and the recorder 316, are located adjacent the manual motor controls, namely the rheostat knob 303, the switch 306 and the reset switch 315.

Sec. 14.—Operation—Electrode Drive Control Circuits

Under starting conditions, the arc voltage is of course high, there being no arc established at the electrode. The reset button 315 must be pushed and held while the electrode is being lowered to a position to start the arc. As mentioned above, the crucible is primed with a pile of titanium sponge at its bottom. This pile is in the shape of a cone and raises to approximately the normal arc length at its center. In the case of titanium at a supply

voltage of 30 volts, the normal arc length is approximately 2½ to 3 inches. After the reset button has been pushed and held down, manual control switch 306 is turned to the "lower" position.

5 This completes an energizing circuit for the lower relay 305.

The relay 325 picking up completes an energizing circuit, traced above, for the motor 143, having a polarity to run the motor in a direction to drive the electrode down. The speed of the motor 143 is now established solely by the setting of rheostat 302.

After the arc is established, the motor is run at a substantially constant speed, which is independent of any changes in potential across the arc, as long as those changes do not exceed a value indicative of extinguishment of the arc. The operator can observe, at tachometer 318, the speed at which the electrode is being driven and can observe the effect of any changes he makes by means of recorder 316.

10 It has been found that this constant speed drive arrangement results in a more uniform operation of the furnace than the prior art arrangements which try to change the speed and position of the electrode to maintain a constant voltage drop across the arc. The arc voltage has a natural tendency to fluctuate due to many causes, such as impurities in the electrode, minor changes in the diameter of the electrode, etc. It has been found that such prior art systems tend to reverse the motor repeatedly, driving the electrode alternately up and down, thereby applying unnecessary shocks to the driven system. If the electrode is one which has been welded somewhere along its length, these repeated reversals apply unnecessary shocks to the weld. If the weld happens to be weak, it may result that the electrode breaks at the weld. These difficulties are avoided by simply running the electrode feeding mechanism at a constant speed as long as the arc voltage does not indicate that the arc is extinguished.

15 In the case of a welded electrode, each weld along the length of the electrode is identified by a narrow neck portion of the electrode, as shown at 36a in Fig. 5. At the start of any run, the operator is provided with a chart showing the location of these necks along the electrode. By observing the fluctuations of the arc voltage, which 20 voltage is recorded on a chart, (recorder 316), he can see a minor increase in the arc voltage when these neck portions pass the arc. These fluctuations on the arc voltage recording chart provide him with a check that the electrode is feeding properly and that all is going well.

25 The particular rate of feed for any given type of electrode is a matter which must be determined empirically from past experience. The operator makes an adjustment in the rate of feed only if he finds that the arc voltage shows a continuous tendency to increase or decrease from 30 its desired value, as opposed to repeated minor fluctuations in value.

35 In any practical apparatus the voltage measured by the recorder 316 is not the potential immediately across the arcs, but is a potential measured between conveniently accessible points in the arc circuit, as close to the arc as is practicable. Consequently, the recorder 316 is measuring the sum of the voltage drop across the arc and other voltage drops in the circuit. All the other voltage drops 40 may be assumed constant except the potential drop along the electrode.

45 As the electrode is fed, the potential drop along the electrode decreases, and the recorder will, under such circumstances, indicate constant voltage only if the arc voltage is increased to compensate for the decrease in the electrode length. The increased arc voltage may be accomplished only by an increase in arc length, with accompanying unstable melting conditions. This condition may be avoided by increasing the feed rate proportionally as 50 the melt proceeds, so that the actual arc voltage remains

substantially constant, and the total recorded voltage decreases to reflect the decrease in electrode length. If the feed rate is properly controlled in this manner, the actual voltage at the arc may be kept nominally constant.

Note, however, that with this novel method of control, the feed is never stopped or reversed. Although changes in the rate of feed may be required, nevertheless in normal operation, the feed rate is kept substantially constant over considerable periods of time.

When it is desired to raise the electrode, the manual control switch 306 is operated to the "raise" position shown in the drawing, closing the circuit for energizing relay 304. The motor 143 is then energized with reverse polarity, and drives the electrode upward.

Sec. 15.—Summary of operation

Section 5 above described the procedure for insertion of a new electrode into the electrode receiving tube. The subsequent steps for converting that electrode into an ingot will now be described.

After the electrode is inserted and the electrode tube cover is in place, the furnace is scavenged with inert gas for a predetermined time, and then evacuated to bring the pressure down to its operating value. The pressure is then held at its evacuated value for several minutes to check the air leak rate. If the leak rate is within satisfactory limits, the power is supplied to the arc. The electrode driving motor is energized for operation in a direction to drive the electrode down and strike an arc at its lower end. As mentioned above, the arc is struck between the lower end of the electrode and a layer of titanium sponge in the bottom of the crucible. During the initial phase of operation, the arc may go out and require restriking. The reset push button 315 which bypasses the arc voltage control is used during starting in order to drive the electrode down initially and in order to drive it down additionally if it becomes necessary to restrike the arc. Once the arc is stabilized and a substantial length of ingot formed in the crucible, then the reset button 315 is not thereafter used if for any reason the arc is interrupted. On the contrary, if that happens the furnace must be shut down and the ingot unloaded before an arc can be struck again. The reason for this is that a restruck arc in the middle of an ingot causes a discontinuity in the ingot crystal structure, which results in flaws in the pieces rolled or otherwise formed from the ingot.

Once the arc is struck, the operator sets the speed control rheostat 309 to establish a constant rate of feed for the electrode. The rate of feed is empirically determined from experience with electrodes of the same diameter and composition, so as to make the feed rate substantially equal to the rate at which material is melted off the electrode minus the rate at which the ingot builds up in the crucible. The operator then watches the record of the arc voltage. If a persisting trend of increase or decrease in the arc voltage is noted, he adjusts the feed rate to compensate for it. A continuing increase in the arc voltage indicates that the feed rate is too slow, and a continuing decrease in it means that the feed rate is too fast. As the electrode moves down, the weld grooves (as shown at 36A in Fig. 5) show temporary increases in the arc voltage because of the smaller current carrying capacity of the reduced diameter electrode at these points. Since the operator is advised at the start of a run just where to expect the weld grooves to appear along the length of the electrode, these grooves provide check points which inform him that the melt is proceeding properly. Conversely, if the arc voltage appears unstable at some other point along the electrode, it indicates to the operator that some condition within the furnace is abnormal.

When the desired length of electrode has been melted, as measured by the integrating Selsyn mechanism, connected to the electrode drive, the operator cuts off the

arc voltage and stops the electrode driving motor. The vacuum pump is maintained running for several minutes thereafter, along with the flow of water or other coolant in the cooling jackets. As soon as the electrode has cooled down sufficiently to allow handling of it, usually a period of several minutes, the crucible is unloaded as described in Section 4 above. The unused butt of the electrode is unloaded, and a new electrode is inserted as described in Section 6.

10 If for any reason the arc voltage is automatically cut off because of a dangerous condition, the procedure thereafter is the same as if the arc voltage supply had been intentionally cut off at the end of a run. No attempt is made to restart the arc with the same electrode and the same ingot after an automatic shutdown.

Sec. 16.—Safety building structure—Figs. 29-31

The crucible chamber 5 is defined on three sides by safety walls 10, 11 and 12. These safety walls are of sufficient thickness and strength to withstand the force of an explosion within the crucible chamber. The exterior wall 13 of the crucible chamber 5 is of much lighter construction, and is known as a blowout wall. For example, in the construction shown, the blowout wall 13 is a rollable corrugated steel curtain which may be extended to the closed position shown or retracted into a housing 14. Outside the blowout wall 13, there is provided a pit 15 defined on the side opposite the blowout wall by a sloping ramp 16 and on its other two sides by steep walls 17 and 18. The walls 17 and 18 terminate at the ground level, so that the pit is open at the top. Set back from the edge of the pit 15 is a steep earth bank or wall 19 which extends from the main wall of the building around the other three sides of the pit 15, although only a portion of the wall 19 is shown in the drawing.

The safety wall 12 is preferably made somewhat thicker and stronger than the other walls, and separates the crucible chamber 5 and a furnace chamber 20 above it from a control chamber 21. The wall 12 is provided with a window 22, through which an operator in the control room 21 may observe the furnace 1. On the wall 12, inside the window 22 there is mounted a steel deflector plate 23 hinged along its bottom edge to the wall 12 just below the window 22 and held in a projecting position between the window and the furnace by means of a prop 26 (see also Fig. 4). The upper surface of the plate 23 carries a mirror 23a. Another mirror 24 is supported on a bracket 25 above the window 22 on the inside of the furnace chamber 20. The operator in the control chamber 21 observes the furnace by looking through the system of mirrors 23a, 24. If an explosion should occur at the furnace, the steel deflector plate would be lifted up from the normal position shown by the force of the explosion and would swing on its hinges so as to cover the window 22. The control chamber 21 is provided with an exit passageway 21a which leads to a door 22 in a wall of the building other than that containing the blowout wall 13.

In the event of an explosion in the crucible chamber 5, which is the locality where the highest temperatures are developed during operation of the furnace, most of the force of the explosion is dissipated through the blowout wall 13, rather than through the three thicker walls. Outside the blowout wall 13, the pit 15 deflects the force of the explosion upwardly. A limited lateral expansion of the gases and other materials expelled by the explosion is permitted at the top of the pit 15, but this lateral expansion can go only as far as the bank 19, where another upward deflection of the force of the explosion takes place. Thus the force of the explosion is dissipated and is directed to a great extent upwardly.

The operating personnel should for the most part be in the control chamber 21 during operation of the furnace. Such personnel are protected from any possible explosion by the wall 12, and by the deflector plate 23. Further-

more, such personnel are provided with an exit passage-way opening to the outdoors at a locality protected by the building structure and the bank 19 from the major force of the explosion.

While I have shown and described a preferred embodiment of my invention, other modifications thereof will readily occur to those skilled in the art and I therefore intend my invention to be limited only by the appended claims.

I claim:

1. An electric furnace comprising a crucible, means including a consumable electrode of material to be treated in said crucible for producing an electric arc therein, means for supplying electric current to said arc-producing means, means for feeding said electrode continuously toward said arc to supply said crucible with material to be melted, and means for controlling said feeding means at a constant rate of advance of said electrode.

2. An electric furnace as defined in claim 1, including means responsive to the electric potential across the arc and operatively connected to said feeding means, and effective as long as the arc potential remains within a range indicative that the arc persists to continue said constant rate of advance, said potential responsive means being effective when said potential shifts to a value outside said range and indicative of interruption of the arc to interrupt operation of the feeding means.

3. An electric furnace as defined in claim 2, including manually operable means to restart said feeding means after interruption thereof.

4. The method of operating a consumable electrode arc furnace, comprising feeding the electrode continuously toward the arc at a rate substantially equal to the rate of melting of the electrode at the arc and independently of fluctuations of the arc voltage over a predetermined range.

5. The method of claim 4, including stopping the feeding of the electrode only if the arc voltage exceeds a value indicating that the arc has been interrupted.

6. An electric furnace comprising a crucible, an elongated consumable electrode of material to be treated in the crucible, electrode supporting means engaging an upper portion of the electrode and supporting the electrode with at least its lower end within the crucible, means including the electrode for producing an electric arc between the lower end of the electrode and a pool of molten material in the furnace, means for supplying electric current to the arc producing means, means for feeding the electrode continuously downward to supply material to the molten pool, means operable to control the rate of downward feed, and means to interrupt the downward feed of the electrode only in response to interruption of the arc.
